[57] CLAIM

The ornamental design for a night light, as shown and described.

DESCRIPTION

FIG. 1 is a perspective view of a night light embodying the principles of the present invention, and illustrating the right side thereof;

FIG. 2 is a front view of the night light of FIG. 1;

FIG. 3 is an end view of the night light, the opposite end view being a mirror image thereof; and,

FIG. 4 is a side view of the night light as seen from the left side of FIG. 2, the opposite side thereof being illustrated in FIG. 1.

The broken lines are shown for illustrative purposes only and form no part of the claimed design.
